UNITED STATES PATENT OFFICE.

CHRIST AXMACHER, THOMAS A. GORMAN, AND JAMES HART, OF JOHNSTOWN,
PENNSYLVANIA.

EJECTOR FOR THREAD-ROLLING MACHINES.

1,161,586.

Specification of Letters Patent. Patented Nov. 23, 1915.

Application filed April 29, 1915. Serial No. 24,811.

To all whom it may concern:

Be it known that we, CHRIST AXMACHER, THOMAS A. GORMAN, and JAMES HART, all citizens of the United States, and residing at Johnstown, in the county of Cambria and State of Pennsylvania, have invented certain new and useful Improvements in Ejectors for Thread-Rolling Machines, of which the following is a specification.

10 Our invention relates to machines by which helical threads are rolled upon the ends of cylindrical bolts or rods. In the use of such machines it frequently happens that the bolt or rod on which a thread has just 15 been rolled will stick and remain in position between the dies of the thread rolling machine. When the thread rolling dies do not clear the threaded bolt at the end of the stroke of a thread rolling operation, the bolt 20 is drawn backwardly between the threading dies by the backward movement of the reciprocating threading die, with the result of deforming and distorting the rolled thread on the end of such bolt.

25 One object of our invention is to provide a bolt ejector of novel construction having means whereby the bolts or rods are ejected from between the threading dies at the completion of each thread forming stroke of the 30 thread rolling machine and sticking of the threaded bolts or rods between the dies with the consequent forming of defectively threaded bolts will be prevented and overcome.

35 Other objects of the invention will become apparent as will be more fully described hereinafter and be specifically pointed out in the appended claims.

Referring now to the drawings forming a 40 part of this specification, Figure 1 is a plan of a thread rolling machine having a bolt ejector constructed and arranged and applied thereto in accordance with our invention, the ejector being shown in its retracted or 45 inoperative position. Fig. 2 is a plan of the front or die end of the thread rolling machine of Fig. 1, showing the ejector in bolt ejecting position. Fig. 3 is a longitudinal side elevation showing the front or 50 die end of the machine and the ejector forming this invention. Fig. 4 is an end elevation of the die threading machine of the preceding figures, with the ejector shown as applied thereto in accordance with our invention. Fig. 5 is a detail sectional elevation

showing the construction of the ejector mechanism forming this invention.

In the accompanying drawings, the numeral 2 designates the base or frame of a thread rolling machine, having a die holder 3 with a stationary die 4 removably secured therein and having a cross head slide 5 with the reciprocating cross head 6 mounted therein. The reciprocatory cross head 6 is provided with reciprocating die 7 removably secured thereon, the thread rolling face 8 of the die 3 being arranged opposite the thread rolling face 9 of the die 7. The cross head 6 is connected by a pitman or connecting rod 10 to a crank pin 11 on the spur gear 12 which is mounted on a shaft secured in the bearing 14 forming part of the frame 2 of the thread rolling machine.

The spur gear 12 meshes with the spur pinion 15 on one end of the counter shaft 16, this shaft being mounted in the bearing 17 forming part of the frame 2. The opposite end of the shaft 16 is provided with a spur gear 18 which meshes with a spur pinion 19 on the overhanging end of the pulley shaft 20. The shaft 20 is provided with a pulley 21 which is secured to the spur pinion 19 either directly or through the shaft 20 so as to positively rotate the spur gear 19. The pulley 21 is connected by a bolt (not shown) with a motor driven line shaft or driving motor.

The belt threading machine, in itself, not forming part of our invention, its construction is not described in detail.

Rigidly secured on the top face of the cross head bearing 5 by bolts 22, 22, is a bracket bearing 23, and mounted in this bearing is a vertically extending shaft 24. The shaft 24 is provided with a squared lower end 25 and opposite sides of the squared end 25 are provided with transversely extending recesses or grooves 26 and 27. The shaft 24 is adapted to turn in the bearing 23 and is held in position by means of a set collar 28, this collar having a set-screw 29. The upper end of the shaft 24 is provided with a transversely extending slot or groove 30 and secured on the cylindrical upper end of the shaft is a helically wound spring 31. The upper end 32 of this spring 31 is bent to extend into or through the transverse groove 30 and the opposite end 33 of the spring 31 is bent so as to project downwardly into an opening hole 34 in the 100

flange of the bracket bearing 23. Secured in the transverse recess 27 in the squared end of the shaft 24 is a downwardly and also outwardly curved ejector arm 34 which has a hook 35 on its outer end forming a bolt engaging lug or shoulder thereon. Secured in the other transverse recess 26 in the squared end of the shaft 24 is a horizontally extending yielding spring arm 36. The outer end of this arm is bent or inclined, the inclined portion 37 being adapted to engage or be engaged by the oppositely inclined end 38 of the trigger 39, the trigger being adjustably secured by bolts 40 to one side of the reciprocating cross head 38, so as to bring the trigger into proper striking engagement with the end 37 of the swinging spring arm 36.

In the operation of threading machines equipped with our improved ejector, the threads are rolled on the bolts or rods by the opposing faces 8 and 9 of the threading dies 4 and 7, the die 7 reciprocating forwardly and backwardly in front of the die 4 in the usual known manner. Suitable dies having been positioned on the thread rolling machine the cross head 6 is advanced until the dies 4 and 7 are in the relative position shown in Fig. 2. The trigger 39 is then adjusted and secured on the cross head 6 in position as shown in Fig. 2. As the reciprocating cross head 6, which carries the reciprocating die 7, moves forwardly and the rear end of the die 7 reaches the end of its forward movement position, adjacent to the front end of the die 4, the inclined end 38 of the trigger 39 engages with the inclined face 37 of the spring arm 36 and further movement of the cross head 6 causes the arm 36 to swing and turn the shaft 24 against the opposing action of the spring 31. This movement of the shaft 24 swings the ejector arm 34 into engagement with the bolt or rod between the dies, a short time before the rear end of the reciprocating die travels past the front end of the stationary die 4. Engagement with the bolt prevents further swinging movement of the arm 34 and causes the yielding arm 36 to spring or bend as the movement of the cross head continues in a forward direction. When the dies reach the position shown in Fig. 2, the bolt or rod on which the thread has been rolled is clear of these dies and the spring action of the yielding arm 36 will forcibly eject the bolt which now is in engagement with the outer end of the ejector arm 34. On the return or backward stroke of the reciprocating cross head, the spring 31 on the shaft 24 acts to return the ejector arm 34 into its retracted position shown in Fig. 1. The above described operations are then repeated with the successive bolts or rods.

The advantages of our invention will be apparent to those skilled in the art. By the

provision of our improved ejector mechanism the bolts are forced from between the threading dies of the threading machine at the completion of each thread rolling operation. The apparatus is simple and is easily kept in repair. The ejector mechanism is mechanically actuated, so that the attention of a workman is unnecessary. By its use the number of defectively threaded bolts and rods is greatly lessened and damage to the threads by reason of sticking is entirely overcome.

Modifications in the construction and arrangement of the parts may be made without departing from our invention as defined in the appended claims.

We claim:

1. A bolt ejector for thread rolling machines, comprising a reciprocating cross-head ejecting mechanism movable into and out of bolt ejecting position, and means reciprocating with the cross head of said thread rolling machine for actuating said mechanism in ejecting the bolts.

2. A bolt ejector for thread rolling machines, comprising a reciprocating cross-head ejecting mechanism movable into and out of bolt ejecting position, means reciprocating with the cross head of said thread rolling machine for actuating said mechanism in ejecting the bolts, and yielding means for retracting the bolt ejecting mechanism.

3. A bolt ejector for thread rolling machines comprising a reciprocating cross-head, a yielding bolt ejecting mechanism movably mounted on said machine, said mechanism being adapted to move into bolt ejecting position prior to the completion of the thread rolling operation, and means on the cross head of said thread rolling machine engaging with and actuating said ejecting mechanism, to thereby engage and eject bolts between the dies of said machine at the completion of the thread rolling operation.

4. A bolt ejector for thread rolling machines comprising a reciprocating cross-head, a yielding bolt ejecting mechanism movably mounted on said machine, said mechanism being adapted to move into bolt ejecting position prior to the completion of the thread rolling operation, means on the cross head of said thread rolling machine engaging with and actuating said ejecting mechanism, to thereby engage and eject bolts between the dies of said machine at the completion of the thread rolling operation, and yielding means for returning said ejecting mechanism into position to engage with a succeeding bolt between the dies of said machine.

5. A bolt ejector for thread rolling machines comprising a reciprocating cross-head, a swinging arm movable into and out

- of bolt ejecting position, a yielding arm connected to and arranged to move said swinging arm into bolt ejecting position, and a trigger on the reciprocating cross head of the thread rolling machine arranged to actuate said yielding arm at the end of the thread rolling operation to thereby move said swinging arm into bolt ejecting position.
- 10 6. A bolt ejector for thread rolling machines comprising a reciprocating cross head, a swinging arm movable into and out of bolt ejecting position, a yielding arm connected to and arranged to move said swinging arm into bolt ejecting position, a trigger on the reciprocating cross head of the thread rolling machine arranged to actuate said yielding arm at the end of the thread rolling operation, to thereby move
- 15 20 and hold said swinging arm in bolt ejecting position, and a spring forming means for retracting said arms at the completion of the bolt ejecting movement thereof.
7. A bolt ejector for thread rolling machines, comprising a reciprocating cross head, a swinging arm arranged to eject bolts held between the threading dies, yielding
- means for holding said swinging arm in retracted position, a spring arm for actuating said swinging arm, and a trigger on the 30 reciprocating cross head of said threading machine arranged to engage the spring arm and move said swinging arm into bolt ejecting position at the completion of the thread rolling operation.
- 35 8. A bolt ejector for thread rolling machines, comprising a reciprocating cross head, a swinging arm, a shaft bearing on said machine, a pivot shaft in said bearing to which said swinging arm is secured, a 40 spring on said shaft to hold the swinging arm in retracted position, a shaft actuating arm on said shaft and a trigger on the reciprocating cross head of said machine, said trigger being arranged to engage the 45 shaft actuating arm and move the ejector arm into bolt ejecting position.

CHRIST AXMACHER.
THOMAS A. GORMAN.
JAMES HART.
